(57) **CLAIM**

The ornamental design for a rack for an all terrain vehicle, as shown and described.

DESCRIPTION

FIG. 1 is a top front perspective view of a rack for an all terrain vehicle showing my design;

FIG. 2 is a top rear perspective view thereof;

FIG. 3 is a right side elevational view thereof;

FIG. 4 is a left side elevational view thereof;

FIG. 5 is a rear elevational view thereof;

FIG. 6 is a front elevational view thereof;

FIG. 7 is a top plan view thereof;

FIG. 8 is a bottom view thereof; and,

FIG. 9 is a side elevational view of the present invention with an all terrain vehicle shown in broken lines to illustrate environment.
